METHOD OF REPAIRING SIPHONS

Filed Dec. 5, 1924

Patented Mar. 5, 1929.

1,704,145

UNITED STATES PATENT OFFICE.

JOHN L. NICHOLSON, OF CHICAGO, ILLINOIS, ASSIGNOR TO LOCOMOTIVE FIREBOX COMPANY, OF CHICAGO, ILLINOIS, A CORPORATION OF DELAWARE.

METHOD OF REPAIRING SIPHONS.

Application filed December 5, 1924. Serial No. 754,029.

This invention relates to improvements in methods of repairing siphons and consists of the matters hereinafter described and more particularly pointed out in the appended 5 claims.

The term "siphon" as herein used designates a flat, hollow substantially triangular structure or element particularly adapted for use in locomotive boilers for increasing the 10 water circulation and steaming efficiency thereof. Such an element or thermic siphon is fully shown and described in my prior patent No. 1,337,720 of April 20, 1920, and said element is located in the firebox of the boiler. 15 It generally includes a tubular bottom portion which terminates in a tubular extension or neck which is connected to the inner throat sheet and has a flat hollow body with an elongated discharge mouth, which opens 20 through the crown sheet of the firebox. Being arranged in the firebox, as just mentioned, said tubular neck and adjacent body parts of the siphon which, by reason of being located substantially close to the fire bed on 25 the grate bars, are subjected to the impingement or bombardment of the products of combustion as they pass from the fire bed to the boiler flues. This action of the products of combustion produces a real mechanical wear 30 upon said parts which being assisted by the continuous expansion and contraction under temperature changes, reduces the life of this portion of the siphon below that of the main body part thereof.

35 By reason of their peculiar construction, said siphons are not only difficult to make, but due to the care in which they must be installed, they cost considerable. Heretofore such a worn siphon presented quite a problem. The major portion thereof is still serviceable, but the remaining portion is worn to that degree where safety demands its repair or the replacement of the entire siphon by a new siphon. The replacing of 40 a siphon not only requires a great deal of time and labor to remove the worn siphon but also requires time and labor to reassemble and reweld the new one in place, thus causing a loss of service in said locomotive.

45 My present invention relates to a method of repairing such worn siphons, which method may be readily and economically carried out.

50 One of the objects of the present invention is to provide a simple and efficient method

whereby the worn portion of the siphon may be removed and a new portion substituted therefor, thus restoring the siphon to its original efficiency at but a small expense of time and labor, at the same time reducing the 60 service delay of the locomotive to a minimum.

Other objects of the invention as well as the many advantages thereof will more fully appear as I proceed with my specification.

In the accompanying drawings:

Fig. 1 is a view in side elevation of a siphon element showing the same as it appears relative to the throat sheet and crown sheet of the firebox of a locomotive boiler in which it is installed.

Fig. 2 is a view in side elevation on an enlarged scale of the siphon element after having been repaired by means of my improved method.

Fig. 3 is a perspective view of my improved 75 half siphon or repair element as it appears ready for attachment to a siphon body, after the worn part has been removed.

Fig. 4 is a detail sectional view as taken on the line 4—4 of Fig. 2.

Fig. 5 is a another detail sectional view as taken on the line 5—5 of Fig. 2 and shows the relation of the side walls of the repair element to the side walls of the siphon body.

Fig. 6 is a horizontal section on an enlarged scale as taken on the line 6—6 of Fig. 2 and shows the position of a reinforcing liner at the joint between the siphon body and repair element at the front end of the siphon.

Referring now in detail to that embodiment of the invention illustrated in the drawings, 1 indicates the crown sheet of a locomotive firebox, 2 the inner front throat sheet and 3 indicates as a whole a siphon or water steaming and circulating element installed 90 in the firebox and secured in said crown sheet and front throat sheet, as will soon appear. As described in my patent hereinbefore referred to, said siphon or element includes an upwardly and rearwardly inclined 95 tubular bottom or neck portion 4, and a progressively upwardly enlarging and generally triangular flat hollow body portion 5. The lower part of the bottom portion is a closed tube and constitutes the neck or intake portion 6 of the siphon or element which is in open communication with the front water leg by means of an annularly corrugated dia- 100 phragm plate 7 secured in a suitable opening provided therefor in said throat plate. The 105 110

neck projects into the diaphragm plate and is preferably welded therein, said plate accommodating the expansion and contraction of said element under temperature changes.

5 The hollow body portion 5 comprises parallel side walls 8 and 8^a which are spaced apart a distance less than that approximating the diameter of the tubular or bulged portion 4 which gradually is reduced in width as it approaches the top end of said side walls 8—8^a. Said walls terminate in an outwardly extending flange 9 which is welded into an opening in the crown sheet 1 provided therefor. The front end of the body 5 is defined by a transversely rounded wall 10 which is inclined forwardly and upwardly from the neck 6 as shown and to which it is connected by a curved elbow part 11. Such an element is formed by a single piece of heavy sheet metal folded upon itself with the median line of the tubular part 4 as the line of the fold, the two parts of the element meeting and being welded in a line defining the middle portion of the front wall 10, as shown at 12 in Fig. 4. The top end of the element, inside the flange 9 provides a discharge mouth which opens through the crown sheet to discharge water and steam into the boiler space above the same. The side walls of the siphon element are suitably stay-bolted to withstand both internal and external pressures and the said stay-bolts 13 are so disposed as to extend in rows parallel with lines defining the outlines of the element as a whole. The neck portion 6 is also stay-bolted as at 14.

In service the lower portion and bottom end of the body 5 together with the neck 6 is subjected to the greatest wear for the reasons before stated. Although the siphons 40 are in active use for a long period of time, before this wear is manifest, inspections thereof from time to time will determine when said element should be repaired. When said repair is to be made the worn part of 45 the siphon or element is removed by cutting the same away as for instance with a torch, along the dotted lines 15 and 16 as shown in Fig. 1, so that one side wall is of a greater vertical height than the other, one line of 50 cutting (15) being arranged in a plane above and the other line of cutting (16) being arranged in a plane below that of a predetermined row of stay-bolts as, for instance, the row indicated by the number 13^a. Said lines 55 of cutting pass through the tubular portion 4 in a common plane at a right angle to said portion as indicated at 17. After said siphon has been cut away as described the stay-bolts 13^a are removed leaving a corresponding row 60 of stay-bolt holes in the bottom of the longer side wall 8. The neck 6 is then removed from its engagement in the diaphragm 7 or said diaphragm may be removed from the throat sheet, either way as desired, depending, of course, upon the condition of the diaphragm.

To take the place of that worn portion of the siphon which has been removed, as above described, I provide a renewal or repair boot or section which is substantially a duplicate of the removed part of the siphon except 70 that I prefer to make the neck thereof a trifle longer so that it may be trimmed to fit the old or new diaphragm plate 7, whichever the case may be. In Fig. 3 I have shown a perspective view of said repair boot or section 75 before it has been installed in place. Said boot or section comprises a tubular portion 4^a which terminates at one end in a tubular neck 6^a. Said tubular portion has parallel side walls 8^b—8^c of different heights, said difference equalling that between the cutaway side walls 8—8^a of the siphon body. Said boot is suitably stay-bolted as at 13^b and the higher side wall 8^b is provided near its edge 80 with a row of stay-bolt holes adapted to register with the row of holes in the longer side wall 8^a of the siphon from which the stay-bolts of the row 13^a were removed as before mentioned. The neck 6^a of said repair boot is stay bolted as at 14^a. The bottom forward ends 8^d of the side walls 8^b and 8^c of the boot are left spaced apart for a distance to leave an opening 8^e; the purpose of which will appear later, but below said opening said side walls meet in an elbow curve 11^a and are welded together to provide a seam 18 which extends to the end of the neck 6^a. Such an element when positioned in place with respect to the cutaway portion of the siphon 3 will be made to fit nicely therein but before applying the same thereto, I find it desirable to apply a liner 19 to the bottom end of the end wall 10, as shown in dotted lines in Fig. 2. In applying this liner I chip out a part of the old weld or seam and after inserting the liner 100 and securing the same therein as by the screw plugs 20—20 I reweld said seam. The bottom end of this liner is left to project below the bottom end of the end wall 10 for a purpose to appear later. 105

When the repair boot or element and the siphon body are properly fitted, they may be jacked up or otherwise temporarily held together and the abutting edges of the side walls 8—8^a and 8^b—8^c are welded together as 110 indicated as at 21—22 (see Figs. 2 and 5). After this has been done, the parts 8^a—8^c of the walls 8^b—8^c of the repair boot are worked around or are folded in toward each other about the projecting bottom end of the liner 115 19 and are then secured thereto by plugs 20^a—20^a, similar to the plugs 20 before mentioned, the meeting edges of said parts 8^a—8^a being welded together and to said projecting end of said liner, as shown at 12^a in Fig. 6. 120 A row of new stay-bolts 13^x is then inserted in place, taking the place of those removed from the row 13^a so that said row of new stay-bolts will be located in a plane between that of the lines of welding 21—22 as best 125

shown in Fig. 5. The neck 6^a of the boot is then inserted in and fitted to the diaphragm plate 7 and welded therein, whether said plate be an old or a new one.

- 5 In this manner a new bottom end is provided for the siphon which will be just as efficient for its intended purpose as an entirely new one. By cutting the side walls of the siphon away, as before described and by providing a boot having side walls as mentioned, I am able to provide a stronger connection or bond between them because the lines of welding 21—22 instead of being in the same plane, are in different planes, thus permitting the 15 use of a row of stay-bolts between said planes so that said walls are indeed rigidly connected together.

My improved method of repairing siphons may be carried out without unduly laying up 20 the locomotive because to replace an entire siphon requires substantially a complete dismantling of the firebox end of the locomotive including a removal of the grate because of the size of the complete siphon. However, in 25 my new method, the operations may be carried on inside the firebox and the worn siphon part may be removed through the fire door opening and a new one introduced into the firebox through said door. Thus, no boiler stay-bolts 30 are unnecessarily disturbed.

While in describing my invention, I have referred to certain details of construction, steps in operation and the like, the same is to be taken as by way of illustration only and 35 therefore I do not wish to limit myself thereto except as may be pointed out in the appended claims.

I claim as my invention:

1. The method of repairing a water steaming and circulating element of a boiler which 40 element has parallel side walls stay-bolted together, said method consisting in removing the worn portion of said element along lines arranged in different planes on opposite side 45 of said element, in providing a new part corresponding to said removed part and fitting the same to the remainder of said element and thereafter welding the fitted parts together.

2. The method of repairing a water steaming and circulating element of a boiler which 50 element has parallel side walls stay-bolted together, said method consisting in removing the worn portion of said element along lines arranged in different planes on opposite side 55 of said element, in providing a new part having side walls and fitting said side walls to the side walls of the remainder of the element so that they abut one another and then welding said abutting edges together.

60 3. The method of repairing a water steaming and circulating element of a boiler which element has parallel side walls stay-bolted together, said method consisting in removing the worn portion of said element along lines 65 arranged in different planes on opposite side

of said element, in providing a new part corresponding to said removed part and fitting the same to the remainder of said element, in welding the abutting edges of said new part and remainder together and in then providing 70 a row of stay-bolts which connect the sides of said new part and the sides of said remainder together in a plane between said lines of welding.

4. The method of repairing a water steaming and circulating element in a locomotive firebox which element comprises parallel spaced, stay-bolted side walls connected to the crown sheet of the firebox and a tubular neck connected to the inner throat sheet of the firebox, which method consists in cutting away 80 the worn part of said element along lines arranged in different planes on opposite side walls of the element and in removing the neck from said throat sheet, in providing a new part to take the place of the removed part and which new part has side walls which are fitted to the side walls of the remainder and a neck, in then welding said fitted edges of the side wall together in abutting relation 85 and then welding the neck of the new part in position with respect to said throat sheet.

5. The method of repairing a water steaming and circulating element in a locomotive firebox which element comprises parallel 90 spaced, stay-bolted side walls connected to the crown sheet of the firebox and a tubular neck connected to the inner throat sheet of the firebox, which method consists in cutting away 95 the worn part of said element along lines arranged in different planes on opposite side walls of the element and in removing the neck from said throat sheet, in providing a new part to take the place of the removed part and which new part has side walls which are fitted to the side walls of the remainder and a neck, in then welding said fitted edges of the side walls together in abutting relation 100 and in then providing a row of stay-bolts between one side wall of the new part and one side wall of the remainder which row of stay-bolts is arranged in a plane between those of said lines of welding connecting the side walls of the new part with the side walls of the remainder of said element 110 and in then welding the neck of said new part in position with respect to said throat sheet.

6. The method of repairing a water steaming and circulating element in a locomotive firebox, which element has parallel stay-bolted side walls connected to the crown sheet of the firebox, a rounded end wall and a tubular bottom portion which terminates in a neck connected to the inner throat sheet of the firebox, which method consists in cutting away 120 the worn part of said elements along a line extending through the tubular portion, the side walls and the rounded end wall of said element in removing said neck from said throat sheet, in securing a liner to the bottom 125 130

end of the said rear wall so that a part of the liner projects below said bottom end of said wall, in providing a new part to take the place of the removed part and in fitting 5 the edges thereof to the edges of said remainder, in welding said parts together along lines defined by said fitted edges, in then securing a portion of said new part to the projecting bottom end of the liner and then securing the neck of said new part in place with 10 respect to said throat plate.

7. The method of repairing a water steaming and circulating element in a locomotive firebox, which element has parallel stay-bolted side walls connected to the crown sheet of the firebox, a rounded end wall and a tubular bottom portion which terminates in a neck connected to the inner throat sheet of the firebox, which method consists in cutting 15 away the worn part of said elements along a line extending through the tubular portion, the side walls and the rounded end wall of said element in removing said neck from said throat sheet, in securing a liner to the bottom 20 end of the said rear wall so that a part of the

liner projects below said bottom end of said wall, in providing a new part to take the place of the removed part and in fitting the edges thereof to the edges of said remainder, in welding said parts together along lines 30 defined by said fitted edges, in folding portions of said new part over upon and securing them to said projecting end of the liner and in then securing the neck of said new part in place with respect to said throat plate. 35

8. An element of the kind described comprising a body portion having side walls and a second portion including a neck and having side walls, the edges of which are formed to fit the contour of the edges of the side walls 40 of said body portion, said edges being arranged parallel but in different planes, a line of weld connecting said edges together and a line of stay-bolts arranged parallel with but intermediate the lines of welding and connecting the side wall of the body portion with an opposite side wall of said second portion. 45

In testimony whereof, I have hereunto set my hand, this 1st day of December, 1924.

JOHN L. NICHOLSON.
